HAIR DYE APPLICATOR

Anne Hunter, New York, N.Y.

Application April 25, 1957, Serial No. 45,888

Term of patent 7 years

(Cl. D86—10)

FIG. 4

Fig. 1 is a perspective view of a hair dye applicator embodying my design;

Fig. 2 is an end view thereof;

Fig. 3 is an enlarged fragmentary view of the opposite end thereof; and

Fig. 4 is a fragmentary view of the handle of the applicator on an enlarged scale, an intermediate portion being broken away for convenience of illustration.

The dominant features of my design reside in the handle portion of my applicator embodying, at its free end, a symmetrical tapered beaver tail and, adjacent its thickened end, a knurled portion as shown in Fig. 4.

I claim:

The ornamental design for a hair dye applicator, substantially as shown and described.
